US00D782457S

(12) **United States Design Patent** (10) **Patent No.:** **US D782,457 S**
(45) **Date of Patent:** **** Mar. 28, 2017**

(54) **MOBILE PHONE**

(71) Applicant: **Samsung Electronics Co., Ltd.**, Suwon-si (KR)

(72) Inventors: **Jisang Park**, Yongin-si (KR); **Kiseong Kim**, Gwangmyeong-si (KR); **Hongku Yeo**, Seongnam-si (KR); **Jin-Hoo Lee**, Seoul (KR); **Jaewoong Chung**, Seongnam-si (KR); **Duyeong Choi**, Anyang-si (KR); **Minhyouk Lee**, Seongnam-si (KR)

(73) Assignee: **SAMSUNG ELECTRONICS CO., LTD.**, Suwon-si (KR)

(**) Term: **15 Years**

(21) Appl. No.: **29/577,843**

(22) Filed: **Sep. 15, 2016**

(30) **Foreign Application Priority Data**

Apr. 14, 2016 (KR) 30-2016-0017737

(51) **LOC (10) Cl.** **14-03**

(57) **CLAIM**

The ornamental design for a mobile phone, as shown and described.

DESCRIPTION

FIG. 1 is a top front perspective view of a mobile phone showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom front perspective view thereof; and,

FIG. 9 is a bottom rear perspective view thereof.

The dashed broken lines in the drawings represent portions of the mobile phone that form no part of the claimed design. The dot-dash broken lines in the drawings define the boundaries of the claimed design and form no part of the claimed design.

1 Claim, 9 Drawing Sheets
